Primary Examiner — Austin Murphy(74) *Attorney, Agent, or Firm* — Nutter McClellan & Fish LLP**CLAIM**

I claim the ornamental design for a card reader device, as shown and described.

DESCRIPTION

FIG. 1 shows a front view of a card reader device according to a first embodiment.

FIG. 2 shows a left side view of a card reader device according to the first embodiment.

FIG. 3 shows a right side view of a card reader device according to the first embodiment.

FIG. 4 shows a top view of a card reader device according to the first embodiment.

FIG. 5 shows a bottom view of a card reader device according to the first embodiment.

FIG. 6 shows a back view of a card reader device according to the first embodiment; and,

FIG. 7 shows a perspective view of a card reader device according to the first embodiment.
